UNITED STATES PATENT OFFICE.

BLOOMFIELD H. HOWARD, OF WASHINGTON, DISTRICT OF COLUMBIA, AND ERNEST J. TURNER, OF PITTSBURGH, PENNSYLVANIA.

ATTACHMENT FOR FEEDERS FOR INGOT MOLDS.

Application filed June 29, 1923. Serial No. 643,538.

To all whom it may concern:

Be it known that BLOOMFIELD H. HOWARD and ERNEST J. TURNER, citizens of the United States, residing, respectively, at Washington, District of Columbia, and Pittsburgh, in the county of Allegheny and State of Pennsylvania, have invented certain new and useful Improvements in Attachments for Feeders for Ingot Molds, of which the following is a specification.

Our invention relates to improvements in attachments for feeders for ingot molds.

The object of our invention is to provide an attachment adapted to fit upon the upper end of the feeder for extending the feeder whereby a longer ingot can be placed in the mold.

Another object of our invention is to provide an attachment of this character having all of the advantages of the solid or one-piece feeder to prevent the seams and so known as "piping" and also reduce segregation to a minimum.

A further object of our invention is to provide an attachment for a feeder so constructed and arranged that it can be readily placed upon the upper end of the ordinary feeder and held against lateral movement with the interior thereof in alignment with the interior of the feeder.

A still further object of our invention is to provide an attachment which can be made of different lengths so that different length ingots can be cast with the same feeder and at the same time provide a cheap and effective structure having certain details of structure and combination of parts hereinafter more fully set forth.

In the accompanying drawings:

40. Figure 1 is a perspective view of an ingot mold showing one of our patented features applied thereto and our attachment applied to the feeder.

45. Figure 2 is a vertical sectional view of Figure 1 showing two sections, one supported by the other, arranged on the upper end of the feeder.

50. Figure 3 is a perspective view of a mold showing the fluted feeder supported therein and having a correspondingly shaped attachment secured thereto and having a modified form of means for holding it against lateral movement on the feeder.

Figure 4 is a view similar to Figure 3 showing another modified form of a fluted feeder attachment.

Figure 5 is a vertical sectional view of an ingot mold and feeder partly in side elevation of a rectangular mold showing the form of securing means shown in Figures 3 and 4 for holding the attachment in the upper end of the feeder.

Figure 6 is a vertical sectional view similar to Figure 5 showing a modified form of attachment.

Figure 7 is a vertical sectional view similar to Figures 5 and 6 showing a still further modified form of attachment.

Figure 8 is a vertical sectional view similar to Figure 7 showing the attachment having elongated lugs extending partially across all four sides for holding it upon the upper end of the feeder.

Referring now to the drawings: 1 represents the ingot mold and 2 the feeder which extends into the ingot mold and is provided on all four sides with vertically disposed ribs 3, the lower ends of which are adapted to rest upon the upper end of the ingot mold and support the same within the mold. While we have shown and described our attachment as applied to this form of feeder, it will be understood that our attachment can be applied to any of the well known form of feeders shown in our numerous patents, provided the feeder has a flat upper end.

Our improved attachment comprises a hollow member 4 having an interior bore 5 of the same diameter as that of the feeder 3 and is provided at its lower end with the outwardly extending flange 6 forming the annular recess 7 to receive the upper end of the feeder and whereby the attachment 4 is held in perfect alinement on the upper end of the feeder to form a longer feeder for casting a longer ingot.

As shown in Figure 2, the second section 8 may be placed upon the upper end of the section 4 for making a longer feeder or sections of different length could be employed.

In Figure 3, instead of having the flange 6 extending continuously around the fluted section 9, we have provided the section 9 with ribs 10 on any number of sides and said ribs strengthening the fluted section 9.

and also extending down below the section, as indicated at 11, so as to engage the outer wall of the fluted feeder 12 so that the walls of the section 9 and the feeder 12 are in the same plane.

In Figure 4 the same principle is involved and like reference numerals indicate like parts. The only difference between Figures 3 and 4 is that Figure 4 shows a greater number of flutes in both the section 9 and the feeder 12.

Referring to Figure 5, the feeder 13 is of a rectangular form, or could be of a circular form, if desired, and said feeder has resting upon its upper end the section 14 which is provided on four sides with the ribs 15 constructed and arranged precisely the same as shown in Figures 3 and 4 and which holds the walls of the feeder 13 and the section 14 in alignment against lateral movement.

In Figure 6 the section 16 is of a greater thickness than the wall of the feeder 17 and has at its lower end an annularly arranged cut out portion 18 of a width equal to the thickness of the feeder 17 and into which the feeder extends, as fully shown, so that the inner walls of the feeder and section are flush. This cut out portion forms an annular flange 19 and the upper end of the section on its outer periphery is cut away, as indicated at 20 so as to receive the annular flange 19 of another section so that two or more sections may be placed one upon the other.

In Figure 7 we have provided the section 21 with four downwardly extending flanges 22 arranged at the corners so that the feeder 23 and the section 21 are held in a position with their interior bore in alignment.

In Figure 8 we have shown a section 24 provided on all four sides with downwardly extending flanges 25 which extend the greater portion of the width of the section 24 and are adapted to engage the outer periphery of the feeder 26 so as to hold the sections against lateral movement on the feeder with their inner walls in perfect alignment.

While we have shown and described a number of modifications of the invention, it will be understood that applicants' invention resides broadly in providing an attachment for a feeder for ingot molds adapted to rest upon the upper end thereof without making any change whatever in the feeder

so as to extend the feeder for casting a longer ingot.

Having thus shown and described our invention, what we claim is—

1. An attachment for feeders for ingot molds, comprising a section located on the upper end of the feeder and having substantially the same cross sectional area.

2. An attachment for feeders for ingot molds, comprising sections located on the upper end of the feeder each of said sections being of substantially the same cross sectional area of the feeder.

3. An attachment for feeders for ingot molds, comprising a section located on the upper end of the feeder and having means for engaging the outer periphery of the feeder for holding it against lateral movement thereon.

4. An attachment for feeders for ingot molds, comprising a section of substantially the same cross sectional area as the feeder and having means extending below the lower end thereof and engaging the outer periphery of the feeder for holding it on the feeder against lateral movement.

5. An attachment for feeders for ingot molds, comprising a section of substantially the same cross sectional area as the feeder and having means around the lower end for holding it upon the upper end of the feeder.

6. An attachment for feeders for ingot molds, comprising a section of substantially the same cross sectional area as the feeder and having means on several sides for engaging the feeder and holding it upon the upper end thereof.

7. An attachment for feeders for ingot molds, comprising a section of substantially the same cross sectional area as the feeder, and having means on several sides extending below the lower end and engaging the outer periphery of the feeder for holding it against lateral movement thereon.

8. An attachment for feeders for ingot molds, comprising a section of substantially the same cross sectional area as the feeder, having strengthening means on its outer periphery extending below the lower end thereof and engaging the outer periphery of the feeder for holding it against lateral movement thereon.

In testimony whereof we affix our signatures.

BLOOMFIELD H. HOWARD.
ERNEST J. TURNER.
